(57) CLAIM

The ornamental design for an earring, as shown and described.

DESCRIPTION

FIG. 1 is a front view of an earring showing the new design; FIG. 2 is a back view thereof;

FIG. 3 is a right side view thereof;

FIG. 4 is a left side view thereof;

FIG. 5 is a bottom view thereof; and,

FIG. 6 is a top view thereof.

The broken lines shown illustrate portions of the earring and form no part of the claimed design.
